UNITED STATES PATENT OFFICE.

JULIUS GOURGUES ACEVES, OF NEW YORK, N. Y., ASSIGNOR TO CROCKER-WHEELER COMPANY, OF AMPERE, NEW JERSEY, A CORPORATION OF NEW JERSEY.

SUPPLY CIRCUITS FOR RADIO SETS.

Application filed April 29, 1922. Serial No. 557,348.

An object of this invention is to provide for the vacuum tubes of such a set means for supplying from a single source of direct current energy a high potential for the 5 plates and a low grid bias voltage which is negative for the amplifier tubes. A further object is to provide a low grid bias voltage from such source which is positive for the detector tubes. A further object 10 of this invention is to provide the source of direct current energy from a commercial alternating current source and deliver direct current of requisite uniformity and voltages to the several parts of a radio set.

15 In the accompanying sheet of drawings which forms a part of this specification, the figure is a diagrammatic representation of one embodiment of the invention in a receiving set.

20 An antenna 1 is connected to ground through an adjustable condenser 2 and an adjustable inductance coil 3. There are three radio frequency tubes 4, 5, 5, and a detector tube 6 connected in cascade. The 25 grid of the first radio frequency tube 4 is shown directly connected to the antenna circuit, the grids of the second and third radio frequency tubes 5, 5 are each connected to the plates of the preceding radio frequency 30 tube inductively through an amplifying transformer with a primary coil 7 and a secondary coil 8. The invention is not limited to any particular number of radio frequency tubes, nor is the invention limited to 35 a single detector tube. The grid of the detector tube is connected to the plate of the last radio frequency tube in cascade inductively through an amplifying transformer with a primary coil 9 and a secondary coil 10. A telephone receiver 11 is connected to the plate of the detector tube and is shunted by a condenser 12.

40 Leads 13, 13 are a source of alternating current, for example, 110 volts at sixty 45 cycles, and connect to a primary coil 14 of a transformer with three secondary coils of which one of the transformer coils 15 is connected to the filaments of the radio frequency tubes and the detector tube. Two 50 secondary coils 16, 17 are connected to two rectifiers 18, 18, the former in a circuit with the filaments and each end of the latter to one of the plates of the rectifiers. From the middle point of one of the secondary coils connected with the rectifier

tubes is a circuit through a filter for suppressing the alternating components, which consists of a series of sections with choke coils or resistances or both 19, 19 in series and condensers of large capacity 20, 20 in 60 multiple. From the further end of the filter the circuit is continued through resistance sections 21, 22, 23 to the middle point of the other of the transformer secondary coils which is connected with the rectifier. The 65 two rectifier tubes are so connected that each passes opposite half waves, and the connections to the circuit through the filter and resistance sections is such that both sets of half waves as impressed on this circuit are 70 of the same sign. Bus-bars 24, 25 are led from the terminals of the series of resistances and between them there will be a difference of potential equal to the voltages 75 of the direct current generated, for example, 125 volts. Bus-bars 26, 27 are led from intermediate points of the series of resistances and the latter is grounded, and the resistances are so proportioned that bus-bar 24 will be 122 volts positive, that bus-bar 26 80 will be 3 volts positive and bus-bar 25 will be 3 volts negative, all with respect to the grounded bus-bar.

85 The primary coils of the transformers which connect the radio frequency tubes are connected to the bus-bar 24 and the far end of the filter. The secondary coils of the transformers which connect the amplifying tubes are connected to the bus-bar 25 on which there is a negative potential of three 90 volts with respect to the filaments. The secondary coil of the transformer between the last of the amplifying tubes and the detector tube is connected to the bus-bar 26 on which there is a positive potential 95 of three volts with respect to the filaments, and the other end of this secondary coil is connected to the grid of the detector tube through a leak resistance 28 shunted by a condenser 29 for the rectification of the 100 signals. The filaments of the amplifying tubes and of the detector tube are connected to two bus-bars 30, 31 which lead from the ends of the secondary coil 15 and the middle point of this secondary coil is grounded so 105 that the filaments will have an average zero potential.

110 The connection of the antenna circuit to ground is through the resistance 23 and a condenser 32 in parallel with the resistance.

All of the apparatus herein described is of familiar construction. The object of the various bus-bars is to light the filaments and impress upon the grids and plates of the tubes the proper voltages with respect to the filaments for straight amplification or rectification as the case may be. Thus for amplification the grid must be negative with respect to the filament, therefore the 10 voltage of the grids of tubes 4, 5, 5, must be negative with respect to the filaments of these tubes which may be about one-fortieth of the plate voltage; but for rectification the grid must have a plus voltage with respect to the filament, and therefore the grid of tube 6 must carry a positive charge with respect to its filament, which is customarily about one-fortieth of the plate voltage.

To this end the system is arranged as 20. hereinafter explained so that the voltages across the bus-bars are as follows: between 24 and 27, for example, 122 volts; between 25 and 27 minus 3 volts; between 26 and 27 plus 3 volts. The voltage between 30 and 31 25 is whatever is necessary and convenient to light the filament with a current of low voltage and high amperage.

The difference of voltage impressed upon the filaments is determined by the number 30 of turns in the secondary coil 15, and the middle point of this coil is grounded. For use with commercial tubes this coil should develop about six volts.

The secondary coil 16 of the transformer 35 will supply about seven volts to light the filaments of the rectifiers. Secondary coil 17 is a high voltage winding. From its two halves in opposite phase, alternating current is carried to the plates of the two rectifiers with the result that a pulsating electro-motive force is carried to the filter by which 40 it is converted into direct current potential. The circuit of the direct current is through the coils or resistances of the filter and the resistances 21, 22, 23 back to the middle 45 point of secondary coil 17.

In ordinary usage bus-bar 25 should have a voltage of about minus 3 volts to which it charges the grids of the amplifier tubes 4, 5, 5; and bus-bar 26 has a voltage of about 50 plus 3 volts to which it charges the grid of the detector tube 6.

An electrical engineer will easily determine the resistances necessary to secure the object set forth in any particular apparatus 55 connected up as herein indicated.

Where a set is so connected a slight but not seriously disturbing hum of a frequency of 120 cycles is heard with the telephone close to the ear, due to the asymmetrical 60 characteristics of the vacuum tubes and to the shift of thermionic current from one end of the filament to the other as the voltages alternate at the rate of sixty per second. From theoretical considerations confirmed by 65 experiment it is found that the disturbance which causes the hum is proportional to the square of the filament voltage. For this reason resistance of filaments of the amplifying and detector tubes should be as low 70 as practicable if an audio-frequency amplifier is desired. For such use tubes should be operated with as low frequency as practicable.

What I claim and desire to secure by 75 Letters Patent of the United States, is—

In a radio set, the combination of an amplifying tube, means for heating the filament of the tube, a connecting circuit, a source of direct-current energy in separate 80 circuits from the circuit for heating the filament having its positive end connected to the plate and its negative end connected to the grid of the tube, a resistance connected between the two ends of the direct-current source, and a conductive connection between an intermediate point of the resistance and the filament circuit, whereby the grid is made more negative than the negative end of the filament.

JULIUS GOURGUES ACEVES.
